(57) **CLAIM**

The ornamental design for an invalid carriage, as shown and described.

DESCRIPTION

FIG. 1.1 is a front perspective view of an invalid carriage showing my new design.

FIG. 1.2 is a rear perspective view thereof;

FIG. 1.3 is a front view thereof;

FIG. 1.4 is a rear view thereof;

FIG. 1.5 is a right side view thereof;

FIG. 1.6 is left side view thereof;

FIG. 1.7 is a top view thereof; and

FIG. 1.8 is a bottom view thereof.

The broken lines in the Figures show portions of the invalid carriage which form no part of the claimed design.
